F. B. ALLDREDGE,
 DEVICE AND PROCESS FOR AUTOMATICALLY REMOVING WATER FROM GAS WELLS,
 APPLICATION FILED JULY 29, 1920.

UNITED STATES PATENT OFFICE.

FRANCIS B. ALLDREDGE, OF DES MOINES, IOWA.

DEVICE AND PROCESS FOR AUTOMATICALLY REMOVING WATER FROM GAS-WELLS.

1,377,171.

Specification of Letters Patent. Patented May 10, 1921.

Application filed July 29, 1920. Serial No. 399,650.

To all whom it may concern:

Be it known that I, FRANCIS B. ALLDREDGE, a citizen of the United States, and a resident of Des Moines, in the county of Polk and 5 State of Iowa, have invented a certain new and useful Device and Process for Automatically Removing Water from Gas-Well, of which the following is a specification.

The object of my invention is to provide a 10 device and a process for automatically removing water from gas wells.

A further object is to provide a device and a process for taking water with the gas from a gas well, and for automatically separating 15 the water from the gas without the loss of gas.

A further object is to provide such a device including a structure, which may be made standard and which can be readily and 20 easily adjusted for use in wells, where there is a variation in pressure from time to time and for use in different wells where the pressure is different.

Still a further object is to provide in such 25 a device a convenient means for fastening together two strings of pipes for lowering them or raising them from the well together.

With these and other objects in view, my invention consists in practising the process, 30 hereinafter more fully set forth, and in the construction and arrangement of the various parts of my device, as illustrated in the accompanying drawings, in which:

Figure 1 shows a vertical, central, sectional view through a gas well equipped 35 with a device embodying my invention, and adapted for use in practising my process.

Fig. 2 shows an enlarged, vertical, sectional view of the device used in connection 40 with water drains for counteracting the pressure of the gas.

Fig. 3 shows a side elevation of two strings of pipe, illustrating the method of connecting the same together; and

45 Fig. 4 shows a detail, sectional view taken on the line 4—4 of Fig. 3.

The difficulties which are encountered in removing water from gas wells are well known. The removal of the water by 50 methods now in use is expensive and uncertain resulting in a considerable loss of the

gas, and sometimes in the destruction or injury of the well.

In my drawings, I have used the reference numeral 10 to indicate generally the ground 55 in which the well is located. In the ground 10 is the well or hole in which is received the ordinary casing 11. Received in the casing and projecting downwardly below the casing is a tube or pipe 12 which is preferably of considerably lesser diameter than the casing. At the lower end of the casing there is provided a packer around the tube 12 for closing the passage in the casing at 60 the lower end thereof around said tube. 65

Extending downwardly through the tube 12 is a gas take-off pipe 15, which takes in the gas and water at its lower end.

At the upper end of the pipe 15 is a controlling valve 16. A pipe 17 leads from the 70 valve 16 to a separating receptacle 18 and enters said tank at a point above the bottom thereof.

Communicating with the upper part of the receptacle 18 and leading therefrom is a 75 gas take-off pipe 19. Leading from the lower part of the receptacle 18 is a pipe 20 with which is connected a pipe 21 extending downwardly into the well. At its lower end the pipe 21 is bent at 22 and extended upwardly at 23.

I have found it most convenient in practice to use a pipe 21 with a return bend, in which case the pipe sections 21 and 22 are arranged quite close together. In lowering 85 the pipe into the well only one string of the pipe is supported by the elevator. Where considerable length of pipe is being lowered, it is sometimes found that the other string breaks off. In order to avoid this, I have 90 provided means for connecting together the two strings of pipe at suitable intervals, preferably at the joints between sections of different strings.

For instance, I have shown in Fig. 3, the 95 strings 21 and 23 of two sections A and B, each connected with an ordinary coupling, C. On each coupling C is a laterally extending lug 21^a, having a corrugated face. The lugs 21^a are each provided with one of 100 a plurality of vertically, aligned, elongated slots 21^b.

The corrugated faces of the lugs of the opposite strings of pipe are placed together and bolts 21^a are inserted through the slots 21^b and receive nuts 21^c.

5 By using the elongated slots 21^b, it is possible to connect together the adjacent strings of pipe, even though there may be some vertical variation in the places where the joints come together.

10 Leading away from the upper end of the pipe 23 is a water discharge pipe 24. It may be seen that the pipes 20, 21, 22, 23 and 24 may be considered as a single water discharge pipe.

15 Connected with the pipe 24 is an upwardly extending pipe section 25, which may also be considered a part of said general discharge pipe.

At the upper end of the well is a closure 20 member 26 through which the various pipes extend, and by which the upper end of the casing is closed.

25 On the upper end of the pipe 25, I preferably mount a removable cap 27 in which is a hole 28 of the proper size.

Extending downwardly over the upper end of the pipe 25 is a pipe 28^a of considerably larger diameter than the pipe 25, having at its upper end a removable cap 29, 30 having a suitable lining or gasket 30 of rubber, cork or any suitable material.

On the lower part of the pipe 28^a is some suitable stop device such, for instance, as the flange 31. The flange 31 is designed to 35 removably support one or more weights such for instance, as the ring 32.

I will now describe the practical use of my improved device and the steps involved in the practice of my process.

40 In installing the water seal pipe, I lower the two strings of pipe together and keep them connected by means of the lugs 21^a already described.

It will be noted that the pipe 13 is open 45 at its lower end, so that gas may pass upwardly into said pipe, which I believe insures a constant and regular pressure against the fluid at the bottom of the well and conduces to the uniform and regular 50 operation of my device.

Whenever the water in the well rises as high as the lower end of the pipe 15, the rush of the upwardly moving gas will draw with it, the water, and keep the water level 55 at the lower end of said pipe. This keeps the well free from any undue amount of water, and makes it possible to take from the well at all times its full capacity of gas.

It will be seen that insomuch as the lower 60 end of the casing 11 is closed and the upper end of the well is closed, the pressure of the gas in the well will force the gas upwardly through the pipe 15, and will carry with it considerable water, vapor or mist.

65 The gas and water will pass into the sep-

arating tank 18, and the water will then drop to the bottom of the tank and pass downwardly into the pipe 20, while the gas may be removed through the gas take-off pipe 19.

Assuming that the discharge end of the pipe 24 is lower than the pipe 17, and that no weight is imposed on the discharge end of the pipe 25, it will be seen that water tending to accumulate in the tank 18 would 75 be discharged through the pipe 25 on account of the tendency of water to seek its level.

It is, of course, well known that the discharge of gas from the well is caused by 80 pressure, and this pressure of the gas in the tank 18 will force the water drawn up through the gas downwardly into the pipes 20 and 21. By using ordinary tables showing the equivalent of pressure and head of 85 water, it is easy to determine how far the gas pressure will force the water downwardly in the pipe 21.

It will be seen that by extending the pipe, for the water take-off, deep enough into the 90 well, it would be possible to maintain at all times a water seal without in any way retarding the discharge of water from the pipe 25. This, however, might involve extending the water take-off pipe a considerable 95 distance into the well, or downwardly below the tank or receptacle 18. In order to avoid the expense and difficulty involved in putting the water take-off pipe too far down into the well, I have provided my present 100 improvement.

In the use of my device, the pipes 21 and 23 must be practically filled with water before the flow of gas and water from the well commences. By using the downwardly extending pipe and the upwardly extending pipe, I have provided a water seal.

In order to avoid extending the pipe too far down into the well, I have provided the means shown in Fig. 2 for imposing weight 110 on the outflowing water, or retarding such flow. It will be seen that I have provided a sort of valve, and that the pipe 28 must be lifted in order to permit water to flow through the hole 28 and then downwardly 115 between the pipes 25 and 28.

The effect of the valve device or weight device may be regulated by removing or adding the weight 32, so as to properly counteract the pressure of the gas in the 120 tank 18 and the pipes 20 and 21, without holding the water back in the tank until it rises too high, and on the other hand without making the retarding device so light as to permit the gas to force the water entirely 125 out of the pipe 21.

It will be seen that with my device, I have simply provided a column of water to overcome or counteract the gas pressure and to provide a water seal for preventing 130

the escape of gas, while permitting the water to flow away.

In my present device, I have reduced the height of the column of water necessary for such purpose, by retarding the outflow of the water by means of the weighted device herein described and shown in Fig. 2.

I realize that a great number of devices might be used for securing the liquid seal, 10 and imposing that pressure on the outflowing water for accomplishing my purpose.

The practice of my process involves the use of a water-take-off pipe for removing the water separated from the gas after the 15 gas has been taken from the well, carrying with it the water, and for providing a water seal for preventing the escape of gas, while permitting the escape of water, and involves also the provision of a means for retarding 20 or imposing that pressure on the outflowing water.

A great many different forms of mechanical structure might be used in the practice of my process without departing from the 25 real principle thereof.

It will be understood that the tank or receptacle 18 must be tall enough, or that a sufficient number of the tanks properly connected together must be used, to make it possible 30 for the gas to fully separate from the water and to be taken off at a point above the water level.

It will be noted that without any variation in principle, and with very slight change 35 in construction, my invention herein described, may be applied to gas pipe lines. All that is necessary is to connect the pipe 21 or its equivalent with a low place in the pipe line and the liquid will be drained off 40 in the way herein described. The device may be adjusted according to the varying pressure in the pipe line by means of the weights already described.

It should perhaps be noted that my device 45 may be used for taking oil from the well with the gas, just as the water is taken and the water and oil may be separated after having been taken from the well. The use of my process makes it possible to profitably 50 operate oil and gas wells which heretofore in many cases have been a total loss or unprofitable.

I claim as my invention:

1. The process of automatically removing 55 water from gas wells, comprising the taking of gas and water together from the well, the separating of the gas from the water, the discharge of the water thus accumulated, through a pipe having a liquid seal, and the 60 imposing of back pressure on the discharging water.

2. The process of automatically removing 65 water from a gas well comprising the placing in a well of a pipe for taking off gas, of such size that the pressure of the gas will

carry with it water as it accumulates in the lower part of the well, the closing of the well except for such pipe, the conducting of the gas through a separating receptacle, and the connecting of the lower portion of said receptacle with a means including a water seal 70 for discharging water from the receptacle, for thereby permitting the escape of water and preventing the escape of gas through the last means, and the provision of a back 75 pressure device for the discharging water.

3. The process of automatically removing water from gas wells and separating it from gas, comprising the utilization of the pressure of the gas in the well for forcing water 80 which may accumulate in the well upwardly out of the well, the passing of the gas and water through a separating receptacle, the drawing of the gas from the upper part of said receptacle, and the taking of water 85 from the lower part of said receptacle by forcing said water by means of the pressure of the gas in the receptacle through a water discharge device so arranged as to maintain a water seal, and imposing back 90 pressure on the discharging water.

4. A device for automatically removing water from gas wells, comprising a pipe for drawing gas and water from a well, a separating receptacle communicating with said 95 pipe, a gas take-off pipe leading from the upper part of said receptacle, a water discharge pipe leading from the lower part of said receptacle, having a liquid seal, and means for imposing back pressure on the 100 water in said water discharge pipe.

5. A device for automatically removing water from gas wells, comprising a pipe for removing gas and water from such a well, a separating receptacle communicating with said pipe, a water discharge pipe leading from said receptacle, having a portion adapted 105 for forming a water seal, and means for imposing back pressure on the water in said water discharge pipe.

6. A device for automatically removing water from gas wells, comprising a pipe for removing gas and water from such a well, a separating receptacle communicating with said pipe, a water discharge pipe leading from said receptacle, having a portion adapted 115 for forming a water seal, means for imposing back pressure on the water in said water discharge pipe, said means being adjustable for regulating the degree of such 120 back pressure.

7. A device for automatically removing water from gas wells, comprising a pipe for removing gas and water from such a well, a separating receptacle communicating 125 with said pipe, a water discharge pipe leading from said receptacle, having a portion adapted for forming a water seal, means for imposing back pressure on the water in said water discharge pipe, said means being ad- 130

justable for regulating the degree of such back pressure, said means including a valve device adapted to be opened by discharging water, and interchangeable weights arranged to be mounted on said valve device.

8. A device for automatically removing water from gas wells, comprising a pipe for taking gas and water from a well, a separating receptacle communicating with said pipe, a gas take-off pipe leading from the upper part of said receptacle, a water discharge pipe communicating with the lower part of said receptacle, and having a portion adapted to form a water seal, and means for 10 imposing back pressure on the water in said water discharge pipe, said means being adjustable for regulating the degree of such back pressure.

9. The process of automatically removing 20 water from gas wells, comprising the taking of water and gas from a well through a pipe, the discharging of said water and gas into a separating receptacle, the removal of the gas from the upper part of said receptacle, 25 the connection with the lower part of said receptacle of a pipe having a portion adapted to form a water seal, and the imposing of back pressure on the water in said discharge pipe.

10. The process of automatically removing 30 water from gas wells, comprising the taking of water and gas from a well through a pipe, the discharging of said water and gas into a separating receptacle, the removal of the gas from the upper part of said receptacle, 35 the connection with the lower part of said receptacle of a pipe having a por-

tion adapted to form a water seal, and the imposing of back pressure on the water in 40 said discharge pipe, by means of an adjustable device, whereby the degree of such back pressure may be regulated.

11. In a device for automatically removing water from gas wells, comprising the combination of a pipe for taking the gas 45 and water from the well, a separating receptacle communicating with said pipe, a gas take-off pipe leading from the upper part of said receptacle, a water take-off pipe leading from the lower part of said receptacle, extending downwardly and having 50 a return bend, whereby said last pipe forms a water seal, and means for connecting together the strings of the last-described pipe.

12. In a device for automatically removing water from gas wells, comprising the combination of a pipe for taking the gas and water from the well, a separating receptacle communicating with said pipe, a gas take-off pipe leading from the upper part of said 60 receptacle, a water take-off pipe leading from the lower part of said receptacle, extending downwardly and having a return bend, whereby said last pipe forms a water seal, and means for connecting together the 65 strings of the last-described pipe, said means comprising couplings, each having laterally extending lugs provided with elongated slots and bolts extended through the slots of the respective lugs for connecting the couplings 70 and strings of pipe together.

Des Moines, Iowa, July 21, 1920.

FRANCIS B. ALLDREDGE.
